UNITED STATES PATENT OFFICE.

SAMUEL POPKY, OF WILKES-BARRE, PENNSYLVANIA, ASSIGNOR OF ONE-HALF
TO A. P. O'MALLEY, OF WILKES-BARRE, PENNSYLVANIA.

LOCK.

No. 905,098.

Specification of Letters Patent.

Patented Nov. 24, 1908.

Application filed May 26, 1906. Serial No. 318,959.

To all whom it may concern:

Be it known that I, SAMUEL POPKY, a citizen of the United States, residing at Wilkes-Barre, in the county of Luzerne and State of Pennsylvania, have invented certain new and useful Improvements in Locks; and I do hereby declare the following to be a full, clear, and exact description of the invention, such as will enable others skilled in the art to which it appertains to make and use the same.

This invention relates to improvements in locks, and more particularly to combination locks.

The invention comprises the production of a suitable casing in which is mounted any suitable number of tumblers of an improved type that are adapted to have their notched portions brought into alinement for permitting the operation of the bolt by the manipulation of a plurality of levers, and improved means for releasing all the tumblers at the same time from their operative position.

The invention further comprises the production of a lock having improved tumblers provided with apertures that are adapted to register when the lock is to be operated, improved means registering with the apertures in said tumblers, and means in connection with said registering means for operating the bolt.

The invention also comprises the production of a lock having tumblers provided with notched portions that may be varied at will, means for operating the bolt brought into operation by the registering of means carried by the knob shaft with the notches in the tumblers, and improved means for positively locking the bolt in its inner or outer position.

The object in view is the production of an improved combination lock that may be set with any combination and operated by means of a plurality of levers for bringing the tumblers into proper position for operating the lock, and means for moving the tumblers from operative position.

Another object in view is the production of an improved combination lock provided with a plurality of tumblers having notches formed therein, means for varying the position of said notches, means secured to the knob shaft for registering with said apertures, means connected with the knob shaft for operating the bolt when the notch engag-

ing means have engaged the notches in the tumblers, and means positioned on the lock casing for holding the bolt either in its open or closed position.

With these and other objects in view the invention comprises certain other novel combinations and arrangements of parts as will be hereinafter more fully described and claimed.

In the accompanying drawings:—Figure 1 is a side elevation of part of a door, showing outside arrangement of my lock, and particularly the tumbler operating means. Fig. 2 is a side elevation of a lock embodying the features of my invention, taken from the opposite side of Fig. 1. Fig. 3 is a front elevation of the mechanism of my invention removed from the casing. Fig. 4 is a vertical section through a lock embodying the features of my invention, the same being shown as taken on line 3—3 of Fig. 3. Fig. 5 is a detail view of one of the tumblers used in my lock, parts being removed to better show the construction of the same. Fig. 6 is a rear elevation of a mechanism embodying the features of my invention, the rear plate of the casing being removed to better disclose same. Fig. 7, is a vertical section on line 2—2 of Fig. 6. Fig. 8 is a fragmentary perspective view showing tumbler operating hooks and means for engaging and disengaging the same, together with surrounding mechanism. Fig. 9 is a section through Fig. 8 approximately on line 9—9, the same having shown in connection therewith the tumblers. Fig. 10 is a section through line 10—10 of Fig. 5.

In the preferred embodiment of my invention, I provide a suitable casing, as 1, which has suitable flanges, as 2 and 3, for securing the casing to a door or the like. Within the casing 1 is located a framework 4 which is held in place by means of lugs 5 and 6 adapted to fit into any suitable openings in the casing 1, and by the rear plate 7, which is secured to the casing by suitable means, as screws 8. The framework 4 has any number of uprights 9—9, which are provided with apertures 10, in which the teeth 11 on the tumblers 12 reciprocate.

Each of the tumblers 12 is so formed as to have a general cylindrical contour and is provided with a flattened surface, as 13, and a series of teeth as 11, which form guides for the same in its reciprocatory movement.

105

110

The teeth 11 slide in the aperture 10 while the flat surface 13 impinges against the rear plate 7, and thus the tumbler 12 is held in proper relation to the uprights 9. I have shown only two tumblers and operating means for the same, but it will be evident that it is within the scope of this invention to use any number of tumblers that may be desired, in order to give a wider range of combination. The tumblers 12 are preferably constructed with a bolt or rounded portion 14, having secured thereto a flange or projection 15 upon which the teeth 11 are formed. Mounted upon the cylindrical portion 14 are any suitable number of plates 16 which are adapted to fit snugly around the portion 14 and the flange or projection 15 and may be removed and rearranged as may be desired. By thus providing the tumbler 12 with a number of plates 16, the notch 17 formed by cutting away a portion of one of the plates 16 may be varied so as to change the combination. After a sufficient number of plates 16 have been placed upon the portion 14 a suitable nut or other securing means is mounted upon the end thereof for holding the same in place.

Secured to the uprights 9 are suitable brackets 18 which carry a shaft 19 on which is mounted a suitable number of operating levers for bringing the tumblers 12 into operative position and then for moving the same from said position. Each of the operating means with its tumbler is identical with all others, and, therefore, it will be sufficient to only describe one of the same in order to give the idea of the complete lock. A lever 20 is mounted upon the shaft 19 and is operated by means of a suitable operating means 21, located on the outside of the lock. Pivotedly connected to the inner end of the lever 20 is a reciprocating bar 22 which is provided with a catch or projection 23, the catch being adapted to normally project into the aperture 10 of the upright 9 in the path of the teeth of the tumbler 12 and engage one of the same. The bar 22 is formed with a cut-away portion 23' which is adapted to accommodate the outer end of a cross-bar 24 which is adapted to hold the bar 22 in such a position as to disengage the catch or projection 23 from the teeth of the tumbler 12 when it is desired to move the tumbler 12 out of operative position. As will be clearly seen from Fig. 4 when the outer end of the lever 20 is depressed, the bar 22 through the medium of the catch 23 will raise the tumbler 12, the cut-away portion 23' permitting the reciprocation of the bar 22, while the cross-bar 24 is permitted to remain in an inoperative position.

Secured to the uprights 9, near one end thereof is a bracket 25 upon which are pivotally mounted bars 26 which extend to and rest upon the cross-bar 24 near the ends

thereof, the bar 24 being cut-away at that point to accommodate bars 26 as well as the bars 22. Each bar 26 is provided with a catch 27 formed integral therewith or secured thereto, the catch being adapted to normally rest within the aperture 10 of one of the uprights 9, and in such a position as to be the distance of one of the teeth 11 on the tumbler 12 from the projection or catch 23 of the bar 22. This particular position of the catch 27 is necessary in order that when the bar 22 is reciprocated and the tumblers 12 are elevated by the raising of the projection or catch 23 means will be provided for holding the same in its elevated position during the return movement of the bar 22. In order to hold the bar 26 and its catch 27 in operative position a spring 28 is mounted upon a shaft 29 one end of which impinges against a lug 30 formed integral with or secured to the bar 26. In order to hold the bar 22 in its operative position a spring, as 31, is secured to the shaft 32 forming a pivotal bearing for the bar 22 one end of which impinges upon a projection 33 secured to or formed integral with the bar 22. By the use of the springs 28 and 31 the catches 23 and 27 are normally held in their operative positions. Secured to or formed integral with the lever 20 is an arm 34 to one end of which a spring 35 is secured thereto, the other end of the spring being fastened to a fixed part of the casing. This arrangement is provided for normally holding the outer end of the lever 20 in an elevated position. The bracket 25 is formed with a vertical portion 36 which is provided with a suitable aperture through which the knob shaft 37 projects. On the outer end of the knob shaft 37 is provided any suitable form of knob 38, while on the inner end of the shaft 37 is positioned a tumbler engaging bar 39 which is preferably beveled at 40 and 41 for permitting the tumblers 12 acting against the beveled surfaces to assist the spring 42 in forcing the tumbler engaging bar 39 out of engagement with the notched portion 17. The tumbler engaging bar 39 is pivotally mounted upon the shaft 37 and will consequently permit the said shaft to revolve without in any way moving the bar 39. The bar 39 is adapted to engage, when in operative position, the notches 17 in the tumblers 12, and when so engaging the notches 17, the shaft 37 will be in such a position as to permit a depending arm 43 to engage the bolt 44 for operating the same. The bolt 44 is normally held in its locked or outer position by a spring 45 and when it has been retracted by means of the projection 43, said bolt will immediately be forced by the spring 45 to its outer position after the operator releases knob 38. Immediately upon the releasing of the knob 38 the projection 43 is permitted, a partial rotation until the 130

same comes opposite cut-away portion 47 when arm 43, together with shaft 37 is moved inwardly by the action of spring 42. From this it will be seen that when the hand 5 of the operator is removed from the knob 38 the shaft 37 will immediately be forced inward by the spring 42 carrying with it the notch engaging bar 39. The rear plate 7 has a cut-away portion 46 through which the 10 bar 39 may reciprocate and the walls of which hold the bar 39 always in position to be drawn forward to engage the notches 17 when the same have been brought into alignment.

15 When it is desired to operate the bolt 44 the levers 20 are operated by means of the operating means 21 and at each depression the tumblers 12 are raised the distance of one tooth. Levers 20 are operated until the 20 notches 17 in tumblers 12 have been raised to a position opposite the bar 39 and then the knob is grasped and pulled outward until the bar 39 engages the notches 17. The 25 reciprocation of the shaft 37 in this direction permits the depending arm 43 to engage the bolt 44 for operating the same. When the notches 17 are in alignment and the depending arm 43 is permitted to engage the bolt 44 the same may be operated as often 30 as desired, but immediately upon releasing the knob 38 the shaft 37 carrying the depending arm 43 will be forced rearward, and consequently the depending arm will be removed from engagement with the bolt 35 44. As long as the tumblers are in such a position as to have the notches 17 in alignment the bolt or knob shaft 37 carrying with it the depending arm 43 may be reciprocated as often as desired, but when any 40 one or all of the tumblers 12 are moved so as to move one or all of the notches 17 out of alignment the shaft 37 cannot be reciprocated and, therefore, the depending arm 43 cannot be brought into engagement with the bolt 44. In order to prevent any damage or 45 mischief being done to the mechanism of the lock the bracket 25 has a cutaway portion 47 which is adapted to receive the arm 43 when the same is in its inner position. The arm 50 43 is rigidly secured to the shaft 37, and consequently when it is in engagement with the bracket 25, the shaft 37 cannot be revolved because of bracket 25 or reciprocated because of tumblers 12.

55 When the tumblers 12 have their notches 17 in alignment and it is desired to change the combination an operating member 48 is depressed which in turn operates a lever 49. When the outer end of the lever 49 is depressed the inner end will raise a reciprocating member 50 which is formed with beveled portions 51-51. When the reciprocating member 50 is raised the beveled surfaces 51 will act against the cross-bar 24 and 60 raise or move the same at right angles to

the uprights 9. When the bar 24 is thus raised or moved it carries with it the bars 22 and 26 with their respective catches. Thus it will be seen when the lever 49 is depressed the catches 23 and 27 are disengaged from the teeth 11, and will permit the tumblers 12 to drop by gravity to their lowermost position against the end of the frame 4. Of course, in order to move the tumblers 12 to their lowermost position, 70 not only the catches 23 and 27 must be disengaged, but also the bar 39. As above described the bar 39 is normally held by the spring 42 out of engagement with the tumblers 12, and, therefore, any time that it 80 is desired to change the combination, it is simply necessary to depress the operating member 48 once and all the tumblers will be forced to their lowermost position.

85 As will be seen from Fig. 6 the notch 17 is positioned at a different place upon the tumblers 12 to their lowermost position, necessary in bringing the tumblers into operative position, that is the notches into alignment, to depress one of the operating means 21 one more time than the other. It 90 will be evident that it is within the spirit of this invention that the notches 17 may be placed at any point along the tumblers 12 so as to give any combination that may be 95 desired.

Formed in the rear plate 7 is an aperture 53 through which projects a pin or lug 54 which is rigidly secured to the bolt 44 and reciprocates with the same. A person desiring to operate the bolt from the inside may do so by simply reciprocating the lug 54. When it is desired to hold the bolt 44 either in its outer or inner position a reciprocating member 55 which is mounted upon the plate 7, is adapted to have one end thereof moved within the path of travel of the lug 54, so that when the member 55 is so positioned as to be in the path of movement of the lug 54, the same cannot be moved and consequently no one can operate the bolt 44 from the outside even if they are familiar with the combination. When it is desired to allow the combination to be used the member 55 is raised and moved to one side and is held in that position by means of a lug 56 engaging the cut-out portion 57 in the member 55. While in this position the bolt 44 may be operated from the inside or from the outside by any one knowing the combination.

Having thus fully described my invention, what I claim as new and desire to secure by Letters Patent is:—

1. A combination lock comprising a bolt, a reciprocating and rotating knob shaft, means secured to said shaft for operating said bolt, tumblers formed with notches therein, means for moving said tumblers to bring the notches thereof into alignment, and a bar 125

pivotally secured to said shaft for engaging said notches, said pivotally mounted cross bar when in engagement with said notches permitting the longitudinal movement of 5 said knob shaft and the engagement of operating means for operating said bolt.

2. A combination lock comprising a bolt, a reciprocating and rotating knob shaft, means secured to said shaft for operating said bolt, 10 a plurality of tumblers, means pivotally mounted on said shaft for engaging said tumblers for permitting said bolt operating means to engage said bolt for operating the same, and means for bringing said tumblers 15 into operative position.

3. A combination lock, comprising a plurality of tumblers each being provided with plates, one of which is cut away to form a notch, said plates being adapted to be re- 20 moved and re-arranged, means for bringing the cut-away plates of all the tumblers into alinement when it is desired to operate said lock, means for engaging said cut-away plates, a knob shaft secured to said engaging 25 means, a bolt, and means secured to said shaft for throwing said bolt.

4. A combination lock comprising a bolt, an arm for throwing the same, a knob shaft for operating said arm, tumblers each provided with plates, one of which being cut away to form a notch on one side thereof, and a rack on the other side thereof, a bar pivotally mounted upon one end of said shaft for engaging said tumblers, said pivotally 30 mounted bar being adapted to engage said cut-away plates to permit the operation of the bolt, and means engaging said racks for bringing the cut-away plates of the tumblers into alinement for permitting said shaft and 35 said operating bar to be moved for permitting said bar to engage said bolt.

5. A combination lock comprising a bolt, operating means for the same held normally out of engagement with said bolt, tumblers 40 formed with notches therein, means for engaging said notches when brought into alinement for permitting said operating means to engage said bolt, and means for moving said

tumblers to bring the notched portions thereof out of alinement for preventing said operating means from engaging said bolt, said means comprising a lever, a reciprocating member formed with beveled portions on one end thereof, and a cross bar designed to be acted upon by said beveled portions. 50 55

6. A combination lock, comprising a bolt, means for operating the same, tumblers for permitting said operating means to be brought into operative position, each tumbler comprising a body portion formed with 60 a rack along one edge, and a plurality of plates partially surrounding said body portion, one of said plates being formed with a cut-away portion, and means for operating said tumblers. 65

7. A combination lock, comprising a bolt, operating means therefor, tumblers for permitting said operating means to be brought into operative position, means engaging said tumblers for raising the same, means for holding the tumblers in a raised position, and means for simultaneously disengaging said raising means and said holding means for permitting all of said tumblers to drop out of operative position, said disengaging 70 means, comprising a lever, and a reciprocating member having beveled portions formed on one end of said member.

8. A lock, comprising a bolt, means for operating the same, normally held out of engagement with said bolt, a lug projecting from said bolt, and means engaging said lug for holding said bolt either in its outer or inner position, said means comprising a pivotally mounted plate formed with a plurality 80 of slots positioned at right angles to each other, and a plurality of lugs engaging said slots for retaining said plate in various positions. 85

In testimony whereof I affix my signature 90 in presence of two witnesses.

SAMUEL POPKY.
